UNITED STATES PATENT OFFICE

2,186,078

DESK TELEPHONE

Alexander C. Reid, Genoa, Ill., assignor to Leich
Electric Co., Genoa, Ill., a corporation of Il-
linois

Application July 5, 1934, Serial No. 733,805

2 Claims. (Cl. 179—100)

My invention relates to desk telephones which are adapted for use with the cradle type or hand set telephone receiver and transmitter.

It is the principal purpose of this invention to provide novel means of mounting the telephone equipment which must be associated with each hand set, such for example, as the dial, the ringer and the hook switch.

It is also a purpose of this invention to provide a device of this character in which all of the equipment is mounted upon a base and a cover for this base carries means for supporting a hand set.

My invention contemplates further the provision of means for removing the cover to gain access to the equipment without disturbing the cords or equipment.

It is a further purpose of my invention to provide in a device of this character a novel mounting for the telephone dial.

Other objects and advantages of the invention will appear as the description proceeds in connection with the accompanying drawings; it is to be understood, however, that the drawings and description are illustrative only and are not to be taken as limiting the invention except in so far as it is limited by the claims.

In the drawings—

Fig. 1 is a vertical section taken through the device;

Fig. 2 is a similar section at right angles to Fig. 1;

Fig. 3 is a detail showing the dial mounting;

Fig. 4 is a detailed view of the mounting of the ringer gongs and coils;

Fig. 5 is a detail showing a side view of the hook switch arrangement; and

Fig. 6 is a view taken at right angles to Fig. 5 of the hook switch mechanism.

Referring now in detail to the drawings, I show at 10 a metal base having the up-turned rim portion 11, upon which the cover 12 is seated. A suitable cushion or pad 13 for the base is adapted to be turned in over the top edge of the rim 11 and held in place by the cover 12 as shown clearly in Figs. 1 and 2. The cover has suitable bosses as indicated at 14 and 15 formed thereon, which bosses are adapted to rest on the punched up posts 16 and 17 of the base. As shown, the bosses are secured on the posts by suitable screws. It is to be understood, of course, that there are more than two bosses and more than two posts.

All of the equipment beneath the cover 12 is mounted upon the base 10 and the cover is readily removable without disturbing the equipment

so that the same may be accessible at any time by just removing the cover. The cover is preferably made of a suitable insulating compound, such for example, as the synthetic resin compounds.

The ringer gong posts 18 and 19 are riveted to the base, for example, by suitable rivets such as 20 and adjustment of the ringer is made by means of the slotted nuts such as 21 and 22, the ringer coils and equipment being supported on the bar 23 which is carried on the posts 18 and 19. The operating mechanism of the ringer forms no part of the present invention, so it will not be described. In front of the ringer there is placed a suitable barrier 24 which separates the ringer casing proper from the rest of the equipment in order that the dust cannot get into the equipment through the openings 25 provided in the ringer side of the cover for the passage of sound waves from the ringer. It will be noted at this point that the cover 12 is not provided with an opening for the lead-in cord 26, but instead is slotted as indicated at 27 so that the cover can be removed without disconnecting the cord.

The terminal block and hook switch mechanism are carried by the U-shaped strap or bracket 28 which has the side pieces 29 and 30 and the cross bar 31 on which the hook switch is supported. The terminal block 32 as shown in Fig. 1 is carried on a shelf 33 formed by punching out a piece of the metal from the legs 29 and 30, it being understood, of course, that there is a shelf on each leg. The hook switch mechanism is suspended from the cross bar 31, which as shown, is provided with the lugs 35 and 36 that are adapted to seat in suitable openings in the top of the legs 29 and 30. The operating stem 37 of the hook switch mechanism projects up through the opening 38 provided in the cover and suitable springs 39 and 40 which are fixed on the cover press down upon the cross bar 31 to hold it in place. The stem 37 is adapted to actuate the contact springs 41 and 42 in the usual manner for opening and closing the hook switch contacts, the lever 43 being engaged by the stem 37 so as to urge the rollers such as 44 and 45 against the contact springs.

The dial mechanism is indicated generally by the numeral 46 and projects through an opening 47 in the front of the cover, this dial mechanism being carried on the hinge bar 48 which is connected by a special hinge structure to the base. The upper end of this bar 48 rests upon a shelf 49 which is part of the member 31 and is 55

pressed downwardly by a suitable spring 50 carried by the cover. The bar 48 is pivoted by means of the slot uprights 51, it being understood that there is one upright at each side in which the extension 52 of the bar is both slideable and rotatable, the uprights being slotted with a slot 53 as shown. The cover thus can be lifted off and the dial will remain in place, then when the cover has been lifted off, the dial mechanism can be folded back into the dotted line position shown in Fig. 3 to permit ready access to the wiring on the back thereof. The induction coil which is housed in the base at 55 and the condenser 56 are fixed on the base so that all of the parts of the telephone are readily accessible when the cover 12 is removed. The condensers 56 are held down by suitable straps such as shown at 57.

From the above description it is believed that the construction and advantages of this device will be clear to those skilled in the art and while I have shown one specific form of my invention, it is obvious that various modifications may be made without departing from the spirit of the invention.

Having thus described my invention, what I claim is new and desire to claim by Letters Patent is:

1. A desk telephone set having in combination a base, a ringing mechanism mounted on said base adjacent one side edge thereof, a dial swingingly secured to said base at the side opposite

said ringing mechanism and projecting upwardly over the base toward the center thereof, a hook switch mechanism mounted on said base between the dial and ringing mechanism mountings, said hook switch mechanism being provided with a shelf upon which the upper end of the dial is supported, and a cover over said mechanism having an opening for said dial and having projections formed thereon for supporting a hand set, said dial being also slideable with respect to the base whereby to permit its movement with the cover as the cover is removed from the base.

2. A desk telephone set having in combination a base, a ringing mechanism mounted on said base adjacent one side edge thereof, a dial swingingly secured to said base at the side opposite said ringing mechanism and projecting upwardly over the base toward the center thereof, a hook switch mechanism mounted on said base between the dial and ringing mechanism mountings, said hook switch mechanism being provided with a shelf upon which the upper end of the dial is supported, and a cover over said mechanism having an opening for said dial and having projections formed thereon for supporting a hand set, said base having a partition member interposed between the ringing mechanism and the hook switch mechanism whereby to isolate the ringing mechanism beneath the cover.

ALEXANDER C. REID.
